LIFTING JACK

Harold W. Clark, Alliance, Ohio, assignor to The Buckeye Jack Manufacturing Company, Alliance, Ohio, a corporation of Ohio

Application February 7, 1930. Serial No. 426,544

3 Claims. (Cl. 254—102)

My invention relates to multiple screw jacks of the type employed for lifting motor cars, although it is not limited thereto, since other uses may be made thereof. In my copending application, Serial No. 322,644, filed November 30, 1928, I have disclosed a lifting jack, of which the present invention is an improvement. As I have explained in said copending application, the chief desiderata in devices of this character are a minimum collapsed height, a maximum extended height, and total enclosure of the working parts, as well as the stability which is made possible by application of the lifting effort near the base of the jack. The structure of the present invention is substantially the same as that of the copending application, but differs therefrom in certain details, which will be emphasized hereinafter, to which the improved results contemplated by the invention are largely due.

For a full understanding of the invention, reference is made to the accompanying drawing, in which

Figure 1 is a top plan view of the jack;

Figure 2 is a central vertical section; and

Figure 3 is a transverse section along the line III—III of Fig. 2.

Referring in detail to the drawing, the jack of my invention comprises a one-piece base 10, having a tubular portion 11 forming a standard. On top of the standard, a thrust-bearing 12 is positioned, and a nut 13 rests on the thrust-bearing. A threaded sleeve 14 is supported within the standard 11 by the nut 13. The sleeve 14 has an internally threaded portion 15 adjacent its upper end for receiving a threaded post 16. The post 16 carries a saddle 16a for engaging the structure to be lifted.

The nut 13 is actuated through a cylinder 17, which is journaled on the standard 11. A ring gear 18 is secured to the cylinder 17 and is adapted to be driven by a beveled pinion 19, which is journaled in a barrel 20 integral with the base 10. The pinion 19 has a shaft portion 21 including a socket 22 for the reception of an operating crank. A split ring 23 cooperates with a groove in the shaft portion 21 to retain the pinion in position.

In order to elevate the jack, a suitably formed crank is inserted in the socket 22 and the pinion 19 is rotated thereby to turn the ring gear 18, the cylinder 17, and nut 13. In order that rotation of the nut 13 cause the elevation of the threaded sleeve 14, I provide means for yieldingly opposing the rotation of the sleeve. Radial holes 24 and 25 are formed in the sleeve near its

lower end. A pin 26 passes through this hole and has a sliding engagement with plungers 27 and 28, the shafts of which are drilled to receive the ends of the pin 26. A spiral spring 29 surrounds the pin and the plunger shafts and is seated under the heads of the plungers to urge them into frictional engagement with the inner wall of the standard 11. This wall is somewhat rough because the base and standard are cast in one piece in a sand mold having a sand core. The slight roughness of this surface affords sufficient frictional engagement with the heads of the plungers 27 and 28 to exert a constant force in opposition to the rotation of the sleeve 14 in the standard 11 in either direction. It is to be understood, however, that this frictional engagement may be overcome by the application of sufficient torque so that the sleeve 14 is forced to turn within the standard, despite the friction of the plungers with the latter. Unless considerable torque is applied, however, the sleeve will not rotate relative to the standard.

Rotation of the nut 13 thus causes the elevation of the sleeve 14 to partially extend the jack. I provide stops 30 and 31, in the form of half turns of a spiral spring, placed within the thread forming the outer surface of the sleeve 14. The springs 30 and 31 have their ends bent so as to enter holes drilled in the root of the thread. When the sleeve 14 has been raised so that the spring 31 engages the lower face of a nut 13, it will be apparent that the sleeve and nut will then be forced to rotate together. Continued rotation of the nut 13, therefore, causes the elevation of the post 16 within the sleeve 14. Obviously, the post is carried up with the sleeve as the latter is raised. The elevation of the jack may thus be continued until the post 16 has reached the limit of its movement. The engagement of the saddle 16a with the object to be raised will prevent rotation of the post with the sleeve and thus insure that the former will be lifted upon rotation of the nut and sleeve.

In general, the saddle will engage its load before the sleeve 14 is fully extended.

The lowering of the jack is accomplished by a reversal of the steps hereinabove outlined. The impedance offered by the frictional engagement of the plungers 27 and 28 with the standard 11 will generally be sufficient to prevent rotation of the sleeve 14 with the nut 13 when the latter is reversed. The sleeve will thus be lowered and the post, in its extended position, will likewise be depressed. This operation continues until the spring 30 engages the upper surface of

the nut, whereupon the sleeve 14 is locked to the nut 13 and rotates therewith. When the sleeve is rotated by the nut, the post is lowered as long as it is prevented from rotating with the sleeve.

5. The present invention is characterized by a simplicity that makes possible the manufacture of the device at a low cost. The complications of the internal structure of the standard which are found in earlier types of jacks are entirely 10 avoided in this form. The interior of the standard is merely a cored-out cylindrical cavity, which requires no machining operations to render it ready for use. The cost of the impedance control means, comprising the plungers 27 and 28, 15 is likewise very small, yet it affords an effective means for controlling the rotation of the sleeve. While the sleeve is being raised or lowered, its rotation with the nut is prevented, but as soon as the sleeve has reached movement of its axial 20 movement, it may be rotated against the opposing force, resulting from the frictional engagement of the plungers with the standard.

It will be obvious that numerous modifications in the construction described may be made. One 25 of the springs 31 may, for example, be omitted and the axial movement of the sleeve may be limited by terminating the screw thread short of the end of the sleeve. Other changes may likewise be found desirable, but any such changes 30 that may be made without departing from the

spirit of the invention are intended to be encompassed within the scope of the following claims.

I claim:

1. In a lifting jack, a standard, a threaded sleeve reciprocable therein, a nut for actuating the sleeve, plungers carried by the sleeve on a pin transverse thereof, having frictional engagement with a substantially unobstructed cylindrical bore in said standard for yieldingly opposing the rotation of said sleeve when the nut is turned, means for limiting the rotation of the nut relative to the sleeve, and a post threaded in said member but maintained against rotation therewith. 80

2. In a jack, a standard, a threaded sleeve reciprocable therein, a nut for the sleeve and spring pressed plungers reciprocable on a common pin carried by the sleeve and frictionally engaging a substantially smooth bore in the standard, for yieldably opposing the rotation thereof. 85

3. A jack comprising a standard having a substantially smooth, cylindrical bore therethrough, a sleeve supported therein, and means for restraining rotation of said sleeve with a substantially constant force including a spring pressed plunger carried on a pin transverse to said sleeve for frictional engagement with said bore. 90
